UNITED STATES PATENT OFFICE

ABRAHAM KLEIN AND LEO ESTEROW, OF NEW YORK, N. Y., ASSIGNORS TO COLUMBIA STAMPING PRODUCTS CO. INC., OF NEW YORK, N. Y., A CORPORATION OF NEW YORK

DESIGN FOR A VANITY CASE OR SIMILAR CONTAINER

Application filed January 31, 1930. Serial No. 34,367. Term of patent 7 years.

To all whom it may concern:

Be it known that we, ABRAHAM KLEIN and LEO ESTEROW, citizens of the United States, and residents of the city, county, and State of New York, have invented a new, original, and ornamental Design for a Vanity Case or Similar Container, of which the following is a specification, reference being had to the accompanying drawing, forming a part hereof, in which:—

We claim:

The ornamental design for a vanity case or similar container, as shown.

ABRAHAM KLEIN.
LEO ESTEROW.
